[57] CLAIM

The ornamental design for a faucet shell, as shown and
described.

DESCRIPTION

FIG. 1 is a top perspective view of a faucet shell show-
ing our new design;

FIG. 2 is a left side elevational view thereof, the right
side being the mirror image of the left side;

FIG. 3 is a top plan view thereof;

FIG. 4 is a front elevational view thereof;

FIG. 5 is a rear elevational view thereof; and

FIG. 6 is a bottom plan view thereof.

The fragmentary broken line representation of a lava-
tory in FIG. 1 is for purposes of illustration only and
forms no part of the claimed design.
